DEFENSIVE PUBLICATION

UNITED STATES PATENT AND TRADEMARK OFFICE

Published at the request of the applicant or owner in accordance with the Notice of Dec. 16, 1969, 869 O.G. 687. The abstracts of Defensive Publication applications are identified by distinctly numbered series and are arranged chronologically. The heading of each abstract indicates the number of pages of specification, including claims and sheets of drawings contained in the application as originally filed. The files of these applications are available to the public for inspection and reproduction may be purchased for 30 cents a sheet.

Defensive Publication applications have not been examined as to the merits of alleged invention. The Patent and Trademark Office makes no assertion as to the novelty of the disclosed subject matter.

Continuation of abandoned application Ser. No. 318,452, Dec. 26, 1972. This application May 17, 1974, Ser. No. 471,090

Int. Cl. G06f 15/20
U.S. Cl. 444—1

38 Sheets Drawing, 82 Pages Specification

In the process described herein, there is sketched on the screen of an interactive graphics display device a front view and a side view of a three-dimensional object such as a polyhedron, a capacitance tablet being a suitable input sketching device. Thereafter, there is described in the front view of the device, a particular surface boundary. The tracking spot on the screen is placed over successive vertex points in the front view and the interactive graphics device lightpen switch is closed at every vertex point. Thereby, there is recorded from the tracking spot position, the Y and Z coordinates of the vertex point in the order in which these points are entered. Next, the same surface is described in the right side view by selecting the vertex points in the same order. A computer determines the X coordinate in this view and since the order of entering data is the same in both views, X values can be assigned to the correct vertex point. The order in which points are entered is the topological map for the surface and the coordinates of all vertex points are known. If

the tracking spot is detected in the right-half of the screen, encoded points are treated as being in the right side view. When the number of points entered for a particular surface on the right side view equal the number of points entered for a particular surface on the front view, the topological description of that surface is completed and an isometric drawing of that surface is projected. Thereafter, another surface is encoded. In the computer, there are compared encoded vertex points to all previously entered points to determine if a new point is within a small error distance of any other point. If it is, then the new vertex point is to be replaced with the previously entered point in the topological map. After an object is completely encoded, in accordance with the process, the orthographic view of the solid object can be rotated for inspection. To determine whether the solid is perfectly encoded, a hidden line test can be made. In this connection, if hidden lines can be eliminated, the vertex list and the topological map are usually correct and complete. The use of the order in which points are entered to construct the topological map and to associate coordinates of points between the front and side views enables complete freedom in the type of polyhedra which can be encoded and the type of graphic material being traced. The process can, therefore, be employed to calculate coordinates and the tedious work of writing down the vertex list and the topological map is eliminated. The process is particularly applicable in numerical control techniques.

ERRATA

In the notices of Defensive Publications appearing on pages 9-12 in the Official Gazette of June 3, 1975, the names of the assignees were omitted and should be added as indicated below:

- T935,001. E. I. du Pont de Nemours and Company, Wilmington, Del.
- T935,002. Pacific Lighting Service Co., Los Angeles, Calif.
- T935,003. International Business Machines Corporation, Armonk, N.Y.
- T935,004. International Business Machines Corporation, Armonk, N.Y.
- T935,005. International Business Machines Corporation, Armonk, N.Y.
- T935,006. E. I. du Pont de Nemours and Company, Wilmington, Del.

In the notices of Defensive Publications appearing on pages 7 and 8 in the Official Gazette of July 1, 1975, the following names of assignees were omitted and should be added:

- T936,001. E. I. du Pont de Nemours and Company, Wilmington, Del.
  - T936,002. E. I. du Pont de Nemours and Company, Wilmington, Del.
  - T936,005. Du Pont of Canada Limited, Quebec, Canada
